ATTORNEY

UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE.

1,070,483.

Specification of Letters Patent. Patented Aug. 19, 1913.

Application filed March 22, 1911. Serial No. 616,157.

To all whom it may concern:

Be it known that I, JACOB KAUFMANN, a citizen of the United States, residing at Philadelphia, in the county of Philadelphia and State of Pennsylvania, have invented 5 certain new and useful Improvements in Heddles, of which the following is a specification.

My invention relates to heddles for loom 10 harness in which the major portion of the heddle is made from a thin flat strip of metal or wire and having means carried at the ends thereof for mounting the heddles on the harness frame rods.

15 My invention also contemplates a construction whereby one or more heddles may be mounted in the frame, either for the purpose of replacing a broken or damaged heddle or where it is desired to increase the number 20 of heddles in the frame, without dismantling the rods from the harness frame.

The nature and characteristic features of 25 my invention will be more readily understood from the following description taken in connection with the accompanying drawings forming part hereof, in which—

Figure 1 is an edge view of a heddle embodying the main features of my present invention, and the same being shown mounted 30 on the rods of the harness frame; Fig. 2 is a face view of the heddle shown in Fig. 1, the harness frame rods being shown in section; and Figs. 3 and 4 are respectively edge and face views, enlarged, of the ends of the heddles shown in Figs. 1 and 2.

In the particular embodiment of the invention which is shown in the drawings 35 is the main or body portion of the heddle which is made from a thin flat strip of metal 40 or wire and in which the warp eye 6 is formed by slitting and expanding in any preferred manner. Near each end of the strip 5 there is provided an aperture 7 in which is arranged a wire loop 8, the loop 8 constituting the means for mounting the heddle on the rods 9 of the harness frame. The loops 8 are preferably made of round 45 hard wire having their ends 10 and 11 abutting or overlapping as clearly shown in Figs. 50 3 and 4, the ends 10 and 11 being capable of being readily sprung apart so that the loops 8 constitute in effect spring snap hooks whereby the heddles may be readily mounted on the rods in any desired location without dis-

mantling the rods from the frame. At the 55 portion of the loop 8 contiguous to the part thereof which engages the aperture 7 of the strip 5, the wire constituting the loop 8 is bent in such manner to form shoulders 12 and 13 to abut or bear against the end of the strip 5 and thereby prevent twisting of the strip relatively to the loop 8 and consequently with respect to the rods so that the strip 5 will always be maintained in a plane parallel to the general extension of 60 the warp which passes through the eye 6 and is controlled thereby, the shoulders 12 and 13 of the loop 8 at one end of the strip serving to prevent rotation in one direction and the corresponding shoulders of the loop 70 8 at the other end serving to prevent rotation in the other direction.

It will be seen that there is provided a heddle in which the major portion thereof may be made of a thin flat strip of metal or 75 wire of relatively small cross-section whereby but little interference will be had with the passing warp threads during the actuation of the harness frames, but in which the loops for mounting the heddles on the harness frame rods may be made of the desired size or outline in those cases where it is necessary to make the rods of considerable thickness and width, as for example in wide installations. It will also be seen that by 80 the construction of the loops 8 as hereinbefore set forth one or more of the heddles may be readily mounted at any desired position in the shaft without dismantling the rods from the frame.

Having thus described the nature and characteristic features of my invention what I claim as new and desire to secure by Letters Patent is:—

1. A heddle made from a thin flat strip of metal or wire having apertures in the ends thereof and wire loops arranged in said apertures for mounting the heddle on the harness frame rods, said loops being bent to 95 form shoulders bearing against the side faces of the strip to prevent rotation of said strip with respect to said loops.

2. Harness for looms comprising supporting rods, a heddle made from a thin flat strip of metal or wire having apertures in the ends thereof, wire loops arranged in said apertures each having a portion surrounding the supporting rods, said loops being 105

bent to form shoulders bearing against the side faces of the strip to thereby prevent rotation of the strip with respect to said loops, and said loops having contiguous ends in the rod surrounding portion adapted to be sprung apart for mounting the heddle in the harness.

In testimony whereof I have hereunto signed my name in the presence of two witnesses.

JACOB KAUFMANN.
